UNITED STATES PATENT OFFICE.

ROBERT M. JOHNSON, OF HAINESPORT, NEW JERSEY.

DESIGN FOR A PRESERVE-JAR CAP.

SPECIFICATION forming part of Design No. 23,144, dated March 20, 1894.

Application filed December 20, 1893. Serial No. 494,203. Term of patent 14 years.

To all whom it may concern:

Be it known that I, ROBERT M. JOHNSON, a citizen of the United States, residing at Hainesport, in the county of Burlington, State of New Jersey, have invented and produced a new and original Design for Preserve-Jar Caps, of which the following is a specification, reference being had to the accompanying drawings, forming part thereof.

The leading feature of my design for a preserve jar cap or cover is a series of bisecting grooves on the upper face of the same.

Figure 1 represents a perspective view of a preserve jar cap embodying my invention. Fig. 2 represents a vertical section thereof on line x, x , Fig. 1.

Similar letters of reference indicate corresponding parts in the two figures.

In the drawings: A designates the cap of a preserve jar, the same having on the upper ²⁰ face thereof a series of bisecting grooves, or radiating grooves B diverging from a common center, said grooves being of different grades.

What I claim is—

The design for a preserve jar cap as shown ²⁵ and described.

ROBERT M. JOHNSON.
